CLAIM

The ornamental design for a cartridge for a conducted electrical weapon, as shown and described.

DESCRIPTION

FIG. 1 is a top, front, right perspective view of a cartridge for a conducted electrical weapon showing our new design; FIG. 2 is a bottom, rear, left perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken lines define the bounds of the claimed design and form no part thereof. The broken lines depicting the remainder of the cartridge for a conducted electrical weapon show features that form no part of the claimed design.
